(57) **CLAIM**

The ornamental design for a driver tool, as shown and described.

DESCRIPTION

FIG. 1 is a perspective view of a driver tool showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of the driver tool, shown in an environment of use; and,

FIG. 10 is a perspective view of the driver tool, shown in an alternate environment of use.

The broken lines illustrate portions of the driver tool that form no part of the claimed design. The broken lines showing a first nose magazine, a battery and a hook in FIG. 9 are for the purpose of illustrating environmental structure, and form no part of the claimed design. The broken lines showing a second nose magazine, a battery and a hook in FIG. 10 are for the purpose of illustrating environmental structure, and form no part of the claimed design.

1 Claim, 10 Drawing Sheets
